UNITED STATES PATENT OFFICE.

ARCHIBALD HOGG, OF NEWCASTLE-UPON-TYNE, ENGLAND.

HATCH-COVER FOR SHIPS.

1,171,721.

Specification of Letters Patent. Patented Feb. 15, 1916.

Application filed June 16, 1915. Serial No. 34,393.

To all whom it may concern:

Be it known that I, ARCHIBALD HOGG, a subject of the King of Great Britain and Ireland, residing at 80 Welbeck road west, 5 Walker, in the city and county of Newcastle-upon-Tyne, England, have invented new and useful Improvements in Hatch-Covers for Ships, of which the following is a specification.

10 This invention relates to hatch covers for ships and other floating structures, and has for its object to provide an improved construction thereof.

A hatch cover made in accordance with 15 this invention is composed of plates shaped and connected together to form corrugations and strengthened and supported by one or more stiffeners arranged transversely of the corrugations of the plating. The corruga- 20 tions of the plating may run in a direction fore and aft of the ship, or in a direction transverse of the ship, but in all cases the stiffeners are arranged at right angles to the corrugations or as nearly so as is compatible 25 with the shape of the hatchway. The stiffeners are shaped to fit the corrugated plating and are attached directly thereto. A single corrugation may be provided in each 30 hatch cover, or two, three, or more corrugations or parts of corrugations may be provided. The corrugations may be of any suitable depth, size and "pitch", and may be arranged on a level or flat plane or in the form of an arch. The widely-spaced stiffeners 35 may be arranged either above or below the plating of the cover. The cover will be supported by the hatch coamings or by the deck as usual, and said coamings may be shaped, if desired, to fit the corrugations at 40 the ends or sides, or end stiffeners may be provided to enter the concavities of the plating and so built up as to provide a plane or other suitable surface where the cover bears on the coamings or deck, these end stiffeners 45 being fitted so as to retain and support the curves or shapes of the corrugated plating, said shaped coamings or end stiffeners closing the ends of the cover transverse of the corrugations thereof.

50 In use the usual canvas covers or tarpaulins may be arranged over the corrugated cover, or a tarpaulin curtain may be fitted around the edges of the corrugated cover, watertightness in either case being obtained 55 by the usual battens, cleats or the like; or

the tarpaulins may be dispensed with and watertightness obtained by means of packing or other methods; or the covers may simply rest in rest pieces on the coaming or on the deck without any tarpaulin or other 60 method of making the cover watertight. The hatch cover may be adapted to be lifted in one piece clear away or turned up on hinges as a whole, or may be formed in any number of parts or portions which may be lifted 65 clear away or turned up on hinges separately. If desired the corrugations may extend the full length of the hatch with no other stiffeners than those attached at the ends. In cases where the cover is divided 70 longitudinally of the corrugations, the end plates at the joints and the end stiffeners of the cover may be the only stiffeners retaining and supporting the corrugated plating.

The accompanying drawings illustrate 75 several constructions of hatchway covers in accordance with my invention.

In the drawings Figures 1, 2 and 3 illustrate a hatch cover having one central stiffener placed on the upper side of the cover 80 and two corrugations in the cover, Fig. 1 being a section on the line V—V in Fig. 3 looking to the left, Fig. 2 a section on the same line looking to the right, and Fig. 3 a section at right angles to Figs. 1 and 2; 85 Figs. 4 and 5 illustrate a hatch cover having one central stiffener placed on the underside of the cover and two corrugations in the cover, Fig. 4 being a similar view to Fig. 1, and Fig. 5 a similar view to Fig. 3. Figs. 90 6, 7 and 8 illustrate a hatch cover in two parts, Fig. 6 being a plan view, Fig. 7 a section on the line W—W in Fig. 6, and Fig. 8 a section on the line X—X in Fig. 6; Figs. 9, 10 and 11 illustrate a hatch cover in four 95 parts, Fig. 9 being a plan view, Fig. 10 a section on the line Y—Y in Fig. 9, and Fig. 11 a section on the line Z—Z in Fig. 9; and Fig. 12 illustrates a modified form of corrugation.

Referring to the drawings, the plating *a* of the hatch cover is shaped to form corrugations as shown, and I employ in combination therewith widely-spaced stiffeners *b* and end stiffeners *c* which close the ends 100 of the cover transverse to the corrugations thereof. The corrugations of the plating may be of curved contour as shown in Figs. 1-11 of the drawings, or they may be of straight-line contour (for example, as 110

- shown in Fig. 12) or of any other suitable contour, and the plates may be lapped as shown and where shown or at any other part of the curve, or they may be butted and strapped. The edges of the plating of the cover at the coamings or rests *d* may be stiffened by angle bars *e* or other suitable section bar, flat or otherwise, or these bars may be dispensed with altogether.
- 10 The corrugations of the cover may be flattened down at the ends of the cover to close the ends transverse of the corrugations as indicated in dotted lines at *f* in Fig. 3 so as to form continuous flat or level portions
- 15 where the ends of the cover bear on the coamings and avoid the necessity of fitting shaped end stiffeners *c*.

The corrugations of the plating *a* may run longitudinally of the hatchway as shown, or they may run transversely of the hatchway, but in all cases the stiffeners *b*, *c* will be arranged at right angles to the corrugations or as nearly so as is compatible with the shape of the hatchway. The stiffeners *b*, *c* are shaped to fit the corrugated plating *a* and are connected directly thereto by angle bars *g* which are also shaped to the corrugations of the plating. The stiffeners are spaced widely apart, the distance

20 between same depending in each case upon the dimensions of the hatch cover. By way of example in a hatch cover 20 feet long by 33 feet wide, the stiffeners will usually be arranged about eleven feet apart, though

25 if desired only one stiffener may be arranged between the end stiffeners or there may be two or more intermediate stiffeners. The stiffeners will usually be fitted across the shorter dimension of the cover and the

30 corrugations of the plating will usually follow the longer dimension of the cover, though this arrangement might be reversed.

The stiffeners may be arranged either above the plating as shown in Figs. 1, 2 and 45 3, or below the plating as shown in Figs. 4 and 5. When the stiffeners are fitted on the upper side of the cover as shown in Figs. 1, 2 and 3 drain holes such as *h* (Fig. 1) may be provided in the stiffeners to allow any water to drain off the top of the cover. When the stiffeners are arranged on the underside of the cover as shown in Figs. 4 and 5, end pieces such as shown at *j* (Fig. 4) may be fitted on the upper side of the cover immediately above the ends of the stiffeners *b*, *c* for the purpose of strength-

ening the ends of the cover to give proper support thereto.

In cases where the cover is made in two or more parts as illustrated in Figs. 6 to 11, separate supporting beams *h* may be fitted, these beams being ordinary hatch beams secured to the coaming *d* as usual and in no way connected to the cover.

The hatch covers illustrated in Figs. 1 to 5 of the drawings are hinged at *m*, the hinges being arranged at the ends of the stiffeners *b* and *c*. In some cases hinges may be fitted at both ends of the stiffeners so that the covers may be turned up on either side as desired, the pivot pins of the hinges at one side of the cover being removed when the cover is to be turned upon the hinges at the other side. If desired, however, the hinges may be dispensed with and the covers adapted to be lifted clear away from the hatchways. The covers of Figs. 6 to 11 are intended to be lifted clear away.

In my improved construction of hatch covers the employment of corrugated plating enables me to dispense with the customary closely-spaced stiffeners which are required and necessary for covers constructed of plane or flat plating and I thereby save weight of steel, and, in addition to this saving of weight, I am enabled to use thinner plating than customary without detracting from the strength of the cover, and I thus greatly reduce the weight of the cover and the cost of same, which saving in weight will add to the carrying capacity of the ship and reduce the appliances and labor required for lifting the covers.

What I claim and desire to secure by Letters Patent is:—

In hatchway covers for ships, the combination of plates shaped and connected together to form corrugations, and stiffeners arranged transversely of the corrugations of said plates, said stiffeners extending into the corrugations of said plates and being attached thereto and means for closing the ends of the covers transverse of the corrugations thereof.

In testimony whereof I have signed my name to this specification in the presence of two subscribing witnesses.

ARCHIBALD HOGG.
